STOKER

Clarence M. Jesperson, Anniston, Ala.

Application June 3, 1943, Serial No. 489,447

7 Claims. (Cl. 110—115)

My invention relates to stokers, more particularly to stokers of the spreader type, and has for an object the provision of apparatus of the character designated which shall be simple of design, economical of manufacture, embody improved fuel distribution means, and be sturdy and rugged in operation and easily regulated.

Further objects of my invention are to provide a stoker which shall include improved rotary spreader means adapted to distribute fuel evenly over a wide fuel bed; a means for varying the trajectory of the fuel discharged from the spreaders and so regulate its distribution longitudinally of the fuel bed; improved means for supplying fuel to the fuel spreaders; and means for limiting the area over which fuel is discharged by the spreader means whereby any selected zone of the fuel bed may be cut off from fuel and cleaned without interfering with the feed to other zones.

My invention still further contemplates the provision of a rotary spreader adapted to cooperate with a substantially horizontal distribution plate to discharge fuel on to the fuel bed, said spreader having a curved active face adapted to provide an even distribution of fuel over the fuel bed.

A more specific object of my invention is to provide an improved rotary spreader having a curved active face, the curvature increasing with the radius of the spreader arms.

A further object of my invention is to provide a stoker having feeder means embodying a distribution plate, and a pair of rotary spreaders adapted to cooperate with the plate to discharge fuel into the furnace, said spreaders having radial arms mounted to rotate above the distribution plate.

The invention by which the foregoing and other objects are attained is illustrated in the accompanying drawings, forming a part of this application, in which

Fig. 1 is a front elevational view of the assembled stoker;

Fig. 2 is a sectional view taken along the line II—II of Fig. 1;

Fig. 3 is a side elevational view of the assembled stoker;

Fig. 4 is a sectional view of the feed screw housing taken along the line IV—IV of Fig. 3;

Fig. 5 is a sectional plan view of the distribution plate and spreaders taken along the line V—V of Fig. 3;

Fig. 6 is a diagrammatic sectional plan view of the spreaders with a furnace fuel bed illustrating the distribution of fuel therein;

Fig. 7 is a detail sectional view showing the

furnace opening and the discharge edge of the distribution plate;

Fig. 8 is a detail view of one of the zoning bars;

Fig. 9 is a detail view of one of the spreaders showing one form of its development; and

Fig. 10 is a bottom plan view of the feed opening in the feed screw housing.

Referring to the drawings for a better understanding of my invention, I show a fragment of a furnace front at 10 which my improved stoker is adapted to serve. The stoker comprises a hopper 11, having the usual feed screw housing 12 at the bottom, in which a feed screw 13 is located. The housing is provided with a delivery opening 14 at the bottom in which is located an adjustable cut off plate 16. See Fig. 10. The cut off plate is supported on lateral guides 15 and is provided with a V-shaped delivery opening 17. Connected to the cut off plate is an adjusting rod 18 mounted in a bracket 19 on the underside of the housing whereby the point of delivery of fuel may be varied.

The feed screw 13 delivers fuel into a spreader housing 21 which has a top opening 22 to receive fuel from the feed screw and a side opening 23 through which fuel is discharged into the furnace. Located within the spreader housing 21 are two rotary spreaders 24 and 26, (see Fig. 5), to be described more particularly hereinafter, which are adapted to discharge the fuel through the side opening 23 of the housing. Mounted within the spreader housing 21 beneath the spreaders 24 and 26 is a distribution plate 27 with which the spreaders are adapted to cooperate. The plate 27 is adjustable vertically by means of set screws 28 and 29 passing upwardly through the bottom of the housing 21 and is maintained in such a position that the spreaders just clear it without dragging. As shown, the distribution plate 27 and spreaders 24 and 26 are mounted horizontally, but if desired they may be tilted so that the fuel discharged by the spreaders may be thrown a greater or lesser distance. A cast rim 25, within the spreader housing 21, forms the outer boundary of the paths of rotation of the spreaders 24 and 26.

Pivotaly mounted in brackets 31 and 32 along the discharge edge of the distribution plate 27 is a discharge lip 33 which has a lower depending flange 34. A set screw 36, mounted in a flange 37, on the underside of the spreader housing 21 bears against the flange 34 and is adapted to adjust the angular position of the discharge lip 33, and thus change the trajectory of fuel being discharged by the spreaders.

At 38 I show a conduit through which the usual

supply of primary air for combustion is supplied. In order to keep the distribution plate 27 cool and to keep fine coal from settling in the discharge opening, I connect conduits 39 and 41 to the conduit 38 and pass them into the feed housing 21 through openings 42 and 43 beneath the distribution plate 27. The air thus admitted is discharged along the discharge edge of the distribution plate 27 through the space 44 between the distribution plate and the adjustable lip 33, and blows away the fines which might otherwise settle in the discharge opening.

Adapted to fit in brackets 46 across the discharge opening 23 of the housing 21 are zoning bars 47, two being provided. See Fig. 8. The zoning bars are each provided with graduations 45 to indicate their positions. By adjusting the positions of the zoning bars 47, any desired area of the fuel bed 48 defined by one wall of the furnace 10 may be cut off from the feed of fuel. This is very important for the reason that by thus cutting off the fuel from certain zones of the furnace, the fuel bed may be cleaned, a part at a time, without interfering with the continued operation of the furnace. Assuming that the zoning bar 47 on the left hand side of the furnace, as viewed in Fig. 6, is so positioned that no fuel is fed on to the fuel bed 48 on the left side, the fuel falling into the feed housing 21 and engaged by the spreader 24 is discharged by the spreader 26 on to the other half of the fuel bed. The half of the fuel bed controlled by the left hand zoning bar 47 may thus be cleaned. The action thus described would be the same if only one spreader, instead of two, were employed as the area controlled by the zoning bars would be the same. For convenience of manufacture and operation, I preferably employ two spreaders.

Referring now particularly to Fig. 9, each of the spreaders has curved radial arms 49 and 51. For even distribution of fuel on the fuel bed, I have found it very important that the active faces 52 and 53 of the arms 49 and 51, respectively, should be convexly curved and preferably have a curvature which increases toward the outer ends of said arms or, stated in another way, the radius of curvature decreases as the outer ends of the arms are approached. I have found that a straight radial arm, or an arm having an active face with a curvature which is the arc of a circle, do not give as satisfactory distribution or trajectory to the fuel being distributed. To those skilled in the art, it will at once be seen that a number of curved surfaces might be developed for the active faces of the arms 49 and 51. For example, the parabola, hyperbola, ellipse, catenary, cycloid, logarithmic spiral, and other curves all embody the principle of a varying curvature and might be adapted for the purpose. By way of example, I show in Fig. 9 the development of surfaces which I have successfully employed, the surfaces 52 and 53 being involute curves generated from circles 54 and 56 which have diameters slightly shorter than the length of said surfaces.

The spreaders 24 and 26 are mounted on shafts 51 and 58 which extend vertically through the upper wall of the housing 21, and each is provided with upper and lower supporting bearings 59 and 61. At the upper end of each of the shafts is a worm gear 62 which meshes with a worm 63 mounted on a worm shaft 64 extending horizontally across between the hopper 11 and the furnace front.

My improved stoker is driven by means of a motor 66, mounted on the furnace front 10, and

is adjustable vertically with respect to its base 67. For the purpose of adjusting the motor, I show an adjusting screw 68 and manual adjusting means 69 on the screw. At 71 I show an adjustable V-belt pulley which connects with the belt 72 to a pulley 73 on the worm shaft 64. By adjusting the distance between the pulleys 71 and 73, I can vary the speed at which the stoker is driven.

On the outer end of the worm shaft 64 is a variable V-belt pulley 74 which connects through a belt 76 with a pulley 77 mounted on a lower worm shaft 78. The worm shaft 78 is provided with a worm 79 which meshes with the worm gear 81 on the end of the feed screw shaft 82, and thus drives the feed screw.

From the foregoing description, the operation of my improved stoker will be readily understood. Fuel is supplied to the hopper 11 and moves by gravity through the open bottom of the hopper into the feed screw housing 12, and is moved by the feed screw 13 to the opposite end where it is delivered through the bottom opening 16 into the spreader housing 21. The V-shaped opening in the feed screw housing is very important in causing a uniform rate of discharge of fuel from the feed screw housing onto the distribution plate. It is also advantageous to regulate, by means of the rod 18, the position of the cut off plate 16 to accommodate the service to which the stoker is subjected. Where the average demand for fuel is heavy, the cut off plate 16 is moved to provide an earlier discharge than in the case of a light average demand. The distribution plate 27 is adjusted by means of set screws 28 and 29 so that it just clears the spreaders 24 and 26. The spreaders rotate in opposite directions, as shown by the arrows in Fig. 5, engage the fuel and distribute it evenly over the entire fuel bed. It is contemplated that primary air for combustion will be supplied beneath the grate 80 shown in Fig. 7 and that secondary air will be supplied beneath the distribution plate 27 as heretofore described. If it be desired to cut off the supply of fuel from either side of the fuel bed 48 in the furnace, the zoning bars 47 are placed in the brackets 46 in front of the side to be cut out. Thereafter all fuel will be discharged by one spreader, the other spreader simply moving its portion of the fuel into the path of the other spreader. The rotational speed of the spreaders and consequently the throw of fuel into the furnace may be regulated by varying the position of the motor 66, thus varying the distance between the variable V-belt pulley 71 and the pulley 73.

From the foregoing it will be apparent that I have devised an improved stoker which is simple and sturdy of design, reliable in operation, and which employs greatly improved fuel distribution means.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are specifically set forth in the appended claims.

What I claim is:

1. In a spreader type stoker, fuel spreading means comprising a distribution plate, a pair of spreaders mounted to rotate above the plate and having radial spreader arms rotating in interengaging paths in the same plane, a housing for the spreaders having an opening along one side

for the discharge of fuel, means to supply fuel to the spreader housing, zoning bars adapted to fit across the discharge opening to limit the area over which fuel is discharged, and an adjustable lip along the discharge edge of the distribution plate adapted to vary the trajectory of fuel discharged.

2. In a spreader stoker, fuel spreader means embodying spreader arms adapted to rotate in opposite directions in interengaging horizontal zones of rotation, parallel vertically disposed shafts upon which the arms are mounted, means to rotate the shafts in opposite directions, a spreader housing having a discharge opening on one side and an opening in the top to receive fuel, a feed screw and housing therefor terminating between the shafts above the spreader arms and adapted to discharge fuel into the spreader housing, and a discharge plate in the bottom of the screw housing above the spreader housing and having a V-shaped discharge opening therein.

3. In a spreader stoker, fuel spreader means embodying spreader arms adapted to rotate in opposite directions in interengaging horizontal zones of rotation, parallel vertically disposed shafts upon which the arms are mounted, means to rotate the shafts in opposite directions, a spreader housing having a discharge opening on one side and an opening in the top to receive fuel, a feed screw and housing therefor terminating between the shafts above the spreader arms and adapted to discharge fuel into the spreader housing, a discharge plate having a V-shaped discharge opening in the bottom of the feed screw housing, and means to adjust the position of the discharge plate longitudinally of the feed screw housing.

4. In a spreader stoker, spreader means comprising a substantially horizontal distribution plate, means to feed coal onto said plate and a spreader embodying a vertically disposed rotary

5 shaft and radial arms on said shaft adapted to rotate in close proximity to the distribution plate, the leading side of each of said arms comprising a convex involute curve generated from a circle having a diameter slightly less than the length 10 of the arm.

5. In a spreader stoker, a rotary spreader rotating about a vertical axis and embodying radial arms having continuous convexly curved active faces in which the radius of curvature decreases 15 from the center of rotation outwards.

6. In a spreader type stoker, a distribution housing, having an opening in the top for receiving fuel and another along one side for discharging fuel, a distribution plate adjustably

20 mounted in the housing to provide an air space therebeneath, means to supply fuel to said plate through said top opening, a pair of spreaders having arms mounted to rotate above said plate with interengaging paths of rotation and to discharge fuel through the said opening, a discharge lip mounted in the discharge opening in spaced relation to the distribution plate to provide an air passage therebetween, and means to supply air under pressure beneath the distribution plate.

25 7. A spreader stoker as defined in claim 1 in which the distribution plate is adjustably mounted in the housing in spaced relation to the bottom thereof, and the adjustable lip is mounted in spaced relation to the discharge plate to provide an air passage therebetween, together with means 30 to supply air under pressure to the housing beneath the distribution plate.

CLARENCE M. JESPERSON.
